Application November 18, 1936, Serial No. 65,995

Term of patent 7 years

To all whom it may concern:

Be it known that I, Max Saldin, a citizen of the United States, resident at Brooklyn, county of Kings, and State of New York, have invented a new, original, and ornamental Design for a Sport Shirt or Similar Article, of which the following is a specification, reference being had to the accompanying drawing, forming a part thereof.

Figure 1 is an elevation of a sport shirt or similar article embodying my new design; and

The characteristic feature of my design resides in the provision of an insert within an insert at the neck portion of the garment, said inserts being of contrasting colors or materials and the body of the garment of a third color or material.

The back of the garment is of the conventional shape and design.

I claim:

The ornamental design for a sport shirt or similar article, as shown and described.
